UNITED STATES PATENT OFFICE.

WALTER S. ADAMS, OF PHILADELPHIA, PENNSYLVANIA, ASSIGNOR TO
JOHN A. BRILL, OF SAME PLACE.

DESIGN FOR A CAR-AXLE BOX.

SPECIFICATION forming part of Design No. 24,756, dated October 15, 1895.

Application filed October 12, 1894. Serial No. 525,725. Term of patent 14 years.

To all whom it may concern:

Be it known that I, WALTER S. ADAMS, a citizen of the United States, residing in the city and county of Philadelphia, State of Pennsylvania, have invented and produced a new and useful Design for a Car-Axle Box, of which the following is a specification.

My invention consists in the configuration of the various parts of the box.

10 In the accompanying drawings, Figure 1 is a front elevation, and Fig. 2 a central vertical section through Fig. 1. Fig. 3 is a side elevation, and Fig. 4 is a plan view.

The general contour of the box at the side and front centrally is rectangular, such portion being at the side indicated by the numeral 1 and in front by the numeral 2.

15 From the central portions 12 depends a rectangular and open lug 3, at each end of which are shoulders 3^a, the outer walls 4 5 of which extend upwardly on the sides of the box and from ribs 6 7 thereon, the rib 7 extending up to the top of the portion 2, which is segmental, as at 8, the rib 6 extending up a portion only 25 of the side of the box and ending at a sub-

stantially circular and annular projection 9 on each side of the box.

At the rear end of the box is a circular projection 10, into which the projections 9 merge, and an annular rib 11 connects the bottom of 30 the projection 10 with the bottom of the lug 3.

A projection 12, lying between the rib 6 and projection 10, is a continuation of the bottom of the main body of the box, of which the upper part 13 of the lug 3 is a part. 35

A rib 14 connects the lower outer portion of the body of the box with the lug 3.

At 15 16 are recesses in the sides of the box, and at 17 is a transverse rib.

Having described my design, I claim— 40

The design for a car axle box, substantially as herein shown and described.

Signed at Philadelphia, in the county of Philadelphia, State of Pennsylvania, this 31st day of August, 1894.

WALTER S. ADAMS.
